[57] CLAIM

The ornamental design for a bottle tray for vehicles, as shown and described.

DESCRIPTION

FIG. 1 is a top, front, and right side perspective view of a bottle tray for vehicles showing my new design;

FIG. 2 is a front elevational view thereof;

FIG. 3 is a rear elevational view thereof;

FIG. 4 is a right side elevational view thereof, the side opposite being similar thereto;

FIG. 5 is a top plan view thereof;

FIG. 6 is a bottom plan view thereof; and

FIG. 7 is another top, front, and right side perspective view thereof with the bottle tray in a folded condition.
